UNITED STATES PATENT OFFICE.

CHARLES K. JENKINS AND HUGH JOSEPH McDONALD, OF SOUTH BUTTE,
MONTANA.

FUSE-IGNITER.

SPECIFICATION forming part of Letters Patent No. 701,203, dated May 27, 1902.

Application filed November 13, 1901. Serial No. 82,154. (No model.)

To all whom it may concern:

Be it known that we, CHARLES K. JENKINS and HUGH JOSEPH McDONALD, citizens of the United States, residing at South Butte, in the 5 county of Silverbow and State of Montana, have invented new and useful Improvements in Fuse-Igniters, of which the following is a specification.

Our invention relates to fuse-igniters, the 10 object of the same being to provide a simple, safe, and reliable device of this kind whereby a plurality of safety-fuses leading to various blasting-holes containing explosive charges may be simultaneously fired.

15 A further object of the invention is to provide a novel construction of igniter of this kind which may be readily connected with the ends of a bunch of fuses and which will serve to cover and protect said ends from water and the like.

Other objects and advantages of the invention will hereinafter appear and the novel features thereof will be set forth in the claims.

In the drawings forming part of this specification, Figure 1 is an elevation showing our improved igniter in operative position. Fig. 2 is a bottom plan view, and Fig. 3 is a vertical central section, of the same.

Like reference-numerals indicate like parts 30 in the different views.

Our improved igniter consists of a shell 1, preferably cone-shaped, having a mass 2 of readily-fusible material therein, the same being retained in place within the shell 1 by 35 means of a disk 3 of wire-netting or other open-work material. The shell 1 is provided with means for holding the disk 3 in position, the same consisting in the form of our invention herein shown of an annular groove 4 on 40 the inside of the shell in which the edges of the disk 3 fit. Outside of the disk 3, but within the shell 1, we may secure in any suitable manner a sheet or disk 6 of combustible waterproof material for the purpose of protecting from dampness the mass 2 of fusible material within the shell, the said disk 6 preferably being of oiled or paraffined paper. The said disk 6 may be held in place within 45 the shell 1 by pasting it around its edges to 50 the inner surface of said shell. In order to provide for the connection of the shell and

the parts carried thereby with the ends of the bunch of fuses 7, we secure to the lower end of said shell 1 attaching devices 8, the same being herein shown in the form of twisted 55 wire. The said wire is passed through openings 9 in the shell 1 and afterward twisted throughout a portion of its length, leaving the ends of the strand of wire free, as shown at 10. When it is desired to connect the igniter with the fuses 7, the twisted portion of the wire 8 is placed in contact with and parallel to the ends of the fuses 7, and the two free ends 10 of said wire are wound around said fuses and also around the twisted portion 60 of said wire. Said free ends 10 are connected to each other by twisting or otherwise and the shell 1 of the igniter is firmly connected with said fuses. The igniter is so disposed on the fuses that the ends of the latter project within or lie adjacent to the lower end of the shell 1 beneath the disks 3 and 6, so that the ends of said fuses are completely protected from water by said shell. Any water that may be falling will be shed from the shell 1 75 and directed away from the fuses 7 by reason of the inclined surfaces of said shell.

The shell 1 may be constructed of tin or other sheet metal, paper, or other material which may be found suitable for the purpose, 80 and for the groove 4, which retains the disk 3 of open-work material in place, any other suitable securing means may be substituted. Other means than the wire 8 may also be provided for connecting the shell 1 to the ends 85 of the bunch of fuses 7.

In using our device it is merely necessary to connect up the shell 1 with the fuses 7 in the manner just described and to fire the mass 2 of explosive material within the igniter. When thus fired, the same acts to ignite the ends of the fuses 7, the disk 6 of waterproof material being consumed and the disk 3 of open-work material serving to distribute the heat or flame equally to all of the 95 fuses 7. It is therefore seen that reliable means are provided for preventing the fuses 7 from becoming wet and for making certain the ignition of all of the fuses 7.

It will be understood, of course, that while 100 it is desirable to ignite all of the fuses 7 simultaneously it is not desirable that all of the

explosive charges in the blasting-holes with which said fuses connect be exploded at the same time. The fuses 7 are therefore made of different lengths, so that the explosive charges in the different blasting-holes will be exploded in succession and in rotation. This enables the best results in the blasting to be obtained, and also provides for the counting of the different explosions, so that the workmen may readily determine when all have taken place, and thereby know when it is safe to return to work. We realize that it is not new to make the fuses of different lengths; but when these fuses are ignited separately by a single workman it frequently happens that after two or three of the fuses have been ignited there will be trouble with the next fuse by reason of the fact that a drop of water has fallen thereon or the igniting-candle has become extinguished, with the result that the workman will be delayed in the operation of igniting the different fuses. During this delay those fuses which have been ignited are burning steadily and the workman either has to get out of the way before he can ignite the remaining fuses, or, as is very often the case, through his anxiety to finish the work he stays a moment too long and his death results. Then, again, according to the old method of igniting the fuses separately the workman may fire a number of holes and in the rush to get away from danger lose count of the number of explosions that take place, or, as very often happens, two or three explosions will take place at the same time, and the workmen, not knowing this to be the case, wait for the number of reports they expect, and if they do not hear them they have to wait for what they consider a sufficient time before returning to their work. This means that sometimes fifteen or twenty men are kept idle for an hour or so. Again, in working in wet places where water is falling if there are two or more holes to blast it requires a man for each hole, and all kinds of maneuvers have to be resorted to in order to keep the water from the ends of the fuses. All of the disadvantages of the old method above referred to are overcome by our invention, which provides not only for the simultaneous ignition of the ends of all of the fuses in the bunch, but provides for the protection against rain of said fuses.

Having now described our invention, what we claim as new, and desire to secure by Letters Patent, is—

1. A fuse-igniter comprising a shell containing fusible material and attaching means on said shell for connecting said shell to the ends of a bunch of fuses, whereby the same are protected and caused to be simultaneously ignited. 60

2. A fuse-igniter comprising a shell containing fusible material, and a wire secured to said shell for connecting the same to a bunch 65 of fuses, whereby the same are protected and caused to be simultaneously ignited.

3. A fuse-igniter, comprising a shell having its upper end closed and containing a mass of fusible substance, a disk of open-work material for retaining said fusible substance in place, and means for connecting said shell to the ends of a bunch of fuses, whereby the same are protected and caused to be simultaneously ignited. 70

4. A fuse-igniter, comprising a shell having its upper ends closed, provided with an annular groove on its inner surface and containing a mass of fusible substance, a disk of open-work material fitting within said groove for retaining said fusible substance in place, and attaching means for connecting said shell to the ends of a bunch of fuses, whereby the same are protected and caused to be simultaneously ignited. 75

5. A fuse-igniter comprising a cone-shaped shell containing a fusible substance and having a groove on its inner surface, a disk of open-work material held in place by said groove, and a wire secured to said shell below said disk for connecting said shell to the ends of a bunch of fuses, whereby the same are protected and caused to be simultaneously ignited. 80

6. A fuse-igniter comprising a cone-shaped shell containing a fusible substance and having a groove on its inner surface, a disk of open-work material held in place by said groove, a disk of combustible waterproof material in said shell beneath said fusible substance, and a wire secured to said shell for connecting the same to the ends of a bunch of fuses, whereby the same are protected and caused to be simultaneously ignited. 85

In testimony whereof we have hereunto set our hands in presence of two subscribing witnesses. 90
